UNITED STATES PATENT OFFICE.

KARL KIEFER, OF CINCINNATI, OHIO.

DESIGN FOR A BOTTLE.

SPECIFICATION forming part of Design No. 35,667, dated February 4, 1902.

Application filed April 1, 1901. Serial No. 53,970. Term of patent 7 years.

To all whom it may concern:

Be it known that I, KARL KIEFER, a citizen of the United States, and a resident of Cincinnati, in the county of Hamilton, in the State of Ohio, have invented a new and original Design for Bottles, of which the following is a specification, reference being had to the accompanying drawings, showing the design.

Figure 1 is a perspective drawing of my design. Fig. 2 is a cross-section, being taken at the height of the line X X.

The leading feature of my design consists in the bottle being of a principally globular

decanter shape, having a fluted neck and a cylindrical part A on the circumference of 15 the bottle, which part is separated from the globular part by raised rings B and B'.

Having described my invention, what I claim as new, and desire to secure by Letters Patent, is—

The design for a bottle as herein shown and described.

KARL KIEFER.
